UNITED STATES PATENT OFFICE.

WILLIAM C. FISHER, JR., OF ATTLEBOROUGH, MASSACHUSETTS, ASSIGNOR
TO ELIAS SOLOMAN, OF NEW YORK, N. Y.

DESIGN FOR A HANDLE FOR NAIL-FILES OR SIMILAR ARTICLES.

SPECIFICATION forming part of Design No. 29,663, dated November 15, 1898.

Application filed October 10, 1898. Serial No. 693,127. Term of patent 3½ years.

To all whom it may concern:

Be it known that I, WILLIAM C. FISHER, Jr., a citizen of the United States, residing at Attleborough, county of Bristol, and State of Massachusetts, have invented and produced a new and useful Design for Handles for Nail-Files and Similar Articles, of which the following is a specification.

In the drawings, Figure 1 represents a view of one face of the handle applied to a nail-file, the opposite face of the handle being a duplicate of the face shown; and Fig. 2, a cross-section on line 2 2.

This design consists of a novel configuration for such articles, presenting a series of raised scrolls of artistic shape, the edges of the handle conforming to the contour of the pattern

substantially shown in the accompanying drawings.

This handle is applied to nail-files, button-hooks, shoe-horns, curlers, brushes, crimps, cuticles, seals, blotters, erasers, darners, and similar articles.

What I claim is—

The design for a handle for nail-files or similar articles, substantially as herein shown and described.

In testimony whereof I hereunto affix my signature, in the presence of two witnesses, this 28th day of September, 1898.

WILLIAM C. FISHER, JR.

Witnesses:

LOUIS C. PORTER,

ORLANDO W. HAWKINS.
